UNITED STATES PATENT OFFICE

AUGUST E. HANSEN, OF EVANSTON, ILLINOIS, ASSIGNEE TO THE SUBTILITE MFG. CO., OF CHICAGO, ILLINOIS, A CORPORATION OF ILLINOIS.

VALVE WITH ACETYLENE LAMP.

1,034,145.

Specification of Letters Patent. Patented Mar. 13, 1914.

Application Feb. 7, 1913. Serial No. 4,264,626.

To all whom it may concern:

Be it known that I, AUGUST E. HANSEN, a citizen of the United States, residing at Evanston, in the county of Cook and State of Illinois, have invented a certain new and useful Improvement in Valve-Stems for Acetylene-lamps, of which the following is a specification.

My invention relates to that class of lamps which are used by miners. In the lamps of this type the valve is usually provided with a knurled head at the top of the valve stem for the purpose of rotating the valve to open or close it. In lamps of this type it is necessary that the head should be very small, and for this reason, the miners find difficulty in operating it.

My invention has for its object to provide means to increase the leverage which can be exerted upon the valve stem by utilizing an essential part of the lamp for this purpose.

My invention has for its further object, in accomplishing this result, to succeed in greatly decreasing the height to which the handle of the clearance rod projects above the top of the lamp.

My means of accomplishing the foregoing may be more readily understood by having reference to the accompanying drawings, which are herein annexed and are a part of this specification, in which:

Fig. 1 is a side elevation of a lamp provided with my improvement, part of the side wall being broken away to show the interior construction, in which the lower end of the water feeding tube and the clearance rod are broken off. Fig. 2 is an enlarged fragmentary detail view of the upper part of the valve stem. Fig. 3 is a top or plan view of the same. Fig. 4 is an enlarged fragmentary detail of the upper end of the clearance rod.

Similar reference numerals refer to similar parts throughout the entire description. As shown in the drawings, the lamp consists of an upper horizontal cylindrical member 1, which forms the water reservoir, and a carbide receptacle 2, which is secured to the water reservoir in the usual manner. 3 is the valve which is provided with a tubular stem 4, the upper end of which is provided with a knurled head 5. Just below

the head 5 are threads 6 adapted to fit into threads cut in the top of the water receptacle. The clearance rod 7 extends through the tubular stem 4 down into the carbide receptacle. This rod fits loosely inside of the tubular valve stem and is adapted to be reciprocated for the purpose of cleaning out a downwardly depending tube 8, which extends down into the carbide for the purpose of carrying the water to or near the bottom of the carbide container.

As thus far described, this is the construction generally employed in lamps of this type. It will be apparent, however, that with the construction thus outlined the loop or handle 9 formed at the top of the clearance rod 7 will project considerably above the top of the knurled head 5 of the valve stem 4. This is objectionable as the miners are desirous of having the lamp as flat as possible on top. It will also be observed that it would be difficult to turn as small a head with any degree of tightness without the aid of pliers or some other similar tool.

I have observed that by cutting a plurality of slots, as at 10 and 11, in the knurled head that the head 9 of the clearance rod 7 can be placed in these slots, thus lowering the head, while at the same time it results in forming practically a wing or thumb nut by which to turn the valve stem and thereby tighten the valve sufficiently without the use of any tools.

It will be apparent that any number of slots can be employed, as shown they are four in number, and it will be observed that the rod is free to be reciprocated when desired without affecting the position of the valve stem.

Having described my invention, what I regard as new and desire to secure by Letters Patent is:

1. The combination with an acetylene lamp having a clearance rod, of a valve, through which said rod passes, a valve stem for said valve, a head on the upper end of said valve stem having a plurality of slots therein adapted to receive the head of the clearance rod, for the purpose set forth, substantially as described.

2. The combination with an acetylene lamp having a clearance rod provided with

a looped head, of a valve, through which said rod passes, a valve stem for said valve, a head on the upper end of said valve stem having a plurality of slots therein adapted 5 to receive the head of the clearance rod, for the purpose set forth, substantially as described.

In testimony whereof I have signed the foregoing specification.

AUGIE L. HANSEN.
